UNITED STATES PATENT OFFICE.

ELIHU THOMSON, OF SWAMPSCOTT, MASSACHUSETTS, ASSIGNOR TO THOMSON ELECTRIC WELDING COMPANY, OF LYNN, MASSACHUSETTS, A CORPORATION OF MAINE.

TRANSFORMER FOR ELECTRIC METAL-WORKING APPARATUS.

SPECIFICATION forming part of Letters Patent No. 783,651, dated February 28, 1905.

Application filed December 4, 1903. Serial No. 183,776.

To all whom it may concern:

Be it known that I, ELIHU THOMSON, a citizen of the United States, and a resident of Swampscott, in the county of Essex and State 5 of Massachusetts, have invented certain new and useful Improvements in Transformers for Electric Metal-Working Apparatus, of which the following is a specification.

My invention relates to that class of electric 10 metal-working apparatus wherein the work is heated by currents of large volume and low electromotive force obtained from the secondary of a transformer. As heretofore operated, this class of apparatus has been supplied with alternating currents for its primary 15 by means of a suitable single-phase generator or supply-circuit, by means of which single-phase alternating currents are caused to pass through the primary and generate the 20 heating-currents for the secondary.

The special object of my invention is to permit the single-phase alternating currents of large volume and low electromotive force supplied to the work to be generated from the 25 primary action of polyphase currents in such manner that the energy shall be drawn equally from the various phases of the polyphase system, so as not to unbalance said system or cause unequal loading of the same.

To this end my invention consists, essentially, in the combination with a welding or metal-working transformer of a primary coil therefor having its terminals connected, respectively, to two wires of a polyphase system 35 and a connection or connections from intermediate portions of said primary to the remaining wires constituting the transmission-circuits of said polyphase system.

My invention consists, further, in the combination with the transformer of an electric metal-working apparatus of an auto-transformer connected to the wires of the transmission-circuits for the polyphase system and having a section connected to the primary of 45 the metal-working transformer.

My invention consists also in other combinations of apparatus and circuits, as herein-after described.

In the accompanying drawings, Figures 1, 2, and 3 represent my invention diagrammatically.

Referring to Fig. 1, S indicates the usual heavy secondary for a metal-working transformer—such, for instance, as a welder—said secondary being preferably of the usual type, comprising a heavy bar or casting of copper, which in its side receives a suitable primary winding, while its terminals are provided with suitable clamping devices B for holding the work W. P indicates the primary for said transformer. It will be understood that the primary and secondary are carried in the usual way on a suitable iron core, as well understood in the art. a b c indicate the mains or transmission-circuits of a polyphase system of two or three phases. To two of the wires of said system, a c, the terminals of the transformer are connected, while the intermediate wire or circuit of the system is connected to an intermediate portion of the primary winding P. It will be understood that the primary is wound for such voltage as to suit the voltage of the polyphase system. By this arrangement of devices the primary P will take energy without unbalancing or loading the system from all wires thereof; but the secondary S will carry the usual single-phase alternating current for heating the work.

In the modification of my invention shown in Fig. 2 the winding P of the metal-working transformer is connected to a section of the winding on an auto-transformer or compensator P², whose terminals and an intermediate portion are connected to the wires of the polyphase system, as shown. The section of said auto-transformer which supplies the currents to the primary P of the metal-working transformer preferably consists of a number of heavier turns in the circuit of the remaining portions of the winding P². As will be understood, the windings P² are on a closed iron circuit or core, as usual in the art.

In Fig. 3 the coils P³ are the primary of a transformer and are connected to the wires or circuits of the polyphase system, as already described, and are adapted to the voltage of

the system, while the secondary S^2 thereof is proper for the winding of the primary P of the welding-transformer. The dotted line L indicates that a middle connection may be made, if desired, between the coils of P and S^2 .

What I claim as my invention is—

1. The combination with a welding or metal-working transformer, of a primary coil therefor having its terminals connected respectively to two wires of a polyphase system and a connection or connections from intermediate portions of said primary to the remaining wires constituting the transmission-circuits of said polyphase system, and a secondary subject to the conjoint action of the sections of primary coil carrying out-of-phase currents so as to be the seat of single-phase currents.
2. The combination with the transformer for an electric metal-working apparatus, of an auto-transformer connected to the wires of the

transmission-circuits for the polyphase system and having a section connected to the primary of the metal-working transformer.

3. In an electric metal-working apparatus, the combination with a metal-working transformer, of a primary coil connected at its terminals to two wires of a polyphase system and having an intermediate connection to a remaining wire of said system, and means for inductively transferring the energy drawn from the whole system to the work as a single-phase alternating current. 25 30

Signed at Lynn, in the county of Essex and State of Massachusetts, this 9th day of November, A. D. 1903.

ELIHU THOMSON.
